WINDOW

Filed April 18, 1925

INVENTOR:
Jesse W. Gross
BY Robert P. Harris
ATTORNEY

UNITED STATES PATENT OFFICE.

JESSE W. GREER, OF CAMBRIDGE, MASSACHUSETTS.

WINDOW.

Application filed April 18, 1925. Serial No. 24,102.

To all whom it may concern:

Be it known that I, JESSE W. GREER, a citizen of the United States, and a resident of Cambridge, in the county of Middlesex 5 and State of Massachusetts, have invented an Improvement in Windows, of which the following description, in connection with the accompanying drawings, is a specification, like characters on the drawings representing 10 like parts.

This invention relates to the window of a confectionery coating machine, and more particularly to means for exerting a continuous lifting force upon the window to hold 15 it in different open positions.

Coating machines such as are used to deposit hot chocolate or icing upon confections are commonly provided with a sliding window that closes an entrance to the 20 coating mechanism, and during the operation of the machine it is necessary to open the window at frequent intervals to obtain access to the coating mechanism and to vary the temperature within the coating machine, and in some cases it may be necessary 25 to raise the window slightly to clear the confections upon the conveyor mechanism.

Since in operating the coating machine it is frequently necessary to raise and lower 30 this window, it is important that the window be constructed so that it will operate easily and will remain in the different positions to which it may be adjusted.

Heretofore counterbalancing weights have 35 been employed to hold the coating machine window in its different positions of adjustment, but such weights are not satisfactory, due to the lack of a sufficient space in which they may be suspended, and to other causes.

The present invention therefore relates to 40 novel means associated with the sliding window of a coating machine for holding the window in its different positions of adjustment.

The various features of the invention will 45 be best understood from the following description when read in connection with the accompanying drawings of a good practical form of the invention.

In the drawings:—

Fig. 1 is a perspective view of a confectionery coating machine provided with a sliding window and having the window supporting means of the present invention associated therewith.

Fig. 2 is a top plan view of the window

supporting portion of the coating machine, with parts shown in section.

Fig. 3 is a front elevation of the portion of the coating machine provided with the 60 sliding window.

Fig. 4 is a sectional view taken on the line 4—4 of Fig. 3; and,

Fig. 5 on an enlarged scale is a sectional view taken on the line 5—5 of Fig. 2. 65

Coating machines of the type with which the present invention is associated usually consist of a closed metal casing 10 and the casing is made relatively tight to prevent the heat of the hot chocolate or other coating 70 material from escaping.

These coating machines are commonly provided with conveyors such as 11 and 12 for passing the confections to be treated thru the coating machine where the coating 75 in a liquid form is deposited upon the confections.

It is necessary to inspect at frequent intervals the operation of the coating mechanism within the casing 10 and these machines are 80 therefore commonly provided with a vertically sliding window 13 thru which the coating operation may be observed. It is also necessary to raise and lower the window 13 at frequent intervals to vary the temperature within the casing 10 and to secure access to the parts within the casing. It is therefore important that the window 13 be so constructed that it will operate easily and will remain at any position to which it may be 85

raised, and, since the coating machine is provided with a large number of operating parts, pipes, etc., the means for holding the window in its different positions of adjustment should be small and compact so as not 90 to interfere with these operating parts, and preferably should be housed to protect its operating parts from the chocolate which may become deposited upon the various parts of the casing 10. The means for holding the window in its different raised positions should also be constructed so that the same will not be injured or disassembled when the coating machine is shipped or 95 moved from place to place in the building in which it is used.

In accordance with the present invention the window 13 is provided with side bars 14 which are rigidly secured in spaced relation by horizontally extending rods 15, the 110 ends of which may be riveted or otherwise rigidly secured to the side bars 14, and a

side face of each of the side bars 14 is provided with rack teeth 16. Within the frame formed by the side pieces 14 and the bars 15 is mounted the sheet of glass 17, and it may 5 be secured in place by providing each bar 15 with a sheet metal strip 18 which is bent about the bar, as best shown in Fig. 5, and has spaced parallel blades disposed at the sides of the sheet of glass, and a sheet of 10 felt or other backing material 19 is preferably provided between the spaced sheets of the strip 18 and the glass 17.

The side bars of the window slide in 15 grooves or slideways formed in the opposite walls of the casing 10 and the window 13 is positioned so that when it is closed its lower edge lies a slight distance above the upper run of the conveyor 11, and when the window is opened it extends upwardly beyond 20 the top 20 of the casing 10. In the construction shown, strips of metal 21 are secured to the opposite sides of the casing 10 so that they extend inwardly a short distance over the side edges of the window 13 25 to retain the same in place in its slideway.

The means of the present invention for exerting a continuous lifting force upon the window to counterbalance its weight consists of gears 22 which are supported above 30 the cover 20 of the coating machine in position to engage the racks 16 of the window, and these gears are preferably rigidly secured to a transversely extending shaft 23 which is rotatably supported near its opposite ends 35 by brackets 24 secured to the top of the casing by bolts 25. The brackets 24 are preferably made hollow so that they will house the gears 22 and the gear receiving opening within each bracket 24 is closed by a cover 40 plate 26 secured in place by screws 27.

In order to exert a rotating force upon the gears 22 which will counterbalance the weight of the window, a relatively long coiled spring 28 is provided about the shaft 45 23 and one end of this spring is secured to a bracket 24 as at 29 and the other end of this spring is secured to a sleeve 30 mounted upon the shaft 23 and rigidly secured thereto by a set screw or the like 31. The spring 28 tends to rotate the shaft and gears in the 50 window lifting direction, and the length of the spring is such that it will rotate the gears thru several complete revolutions to support the window in any position without appreciably decreasing the tension of the spring.

It is desirable to provide a housing for the 55 spring 28 and this is accomplished by providing a tube 32 that extends lengthwise of the shaft 23 about the coiled spring, and one 60 end of this tube may be rigidly secured to the sleeve 30, while the opposite end of this tube may be rotatably supported by an annular projection 33 upon the right-hand bracket 24. The tension of the spring 28 65 may be varied as desired by loosening the set

screw 31 and then rotating the tube 32 upon the shaft 23 until the desired tension is placed upon the spring 28, whereupon the set screw 31 may be tightened to secure the parts in this position of adjustment, and the tension of the spring should be such that it will permit the window to be easily raised and lowered and will support it in any raised position.

As stated, the confectionery coating casing 10 should be approximately air-tight to prevent heat from escaping therefrom, and, in order to provide a tight joint between the window 13 and the cover 20 of the casing, a piece of felt or other soft, flexible material 80 34 is preferably secured to the cover 20, so that its outer edge will rest against the glass 17 of the window to prevent the escape of air between the window and the cover 20.

Claims—

1. In combination with a window mounted for vertical sliding movement in its supporting frame, racks secured to the opposite sides of the window to move up and down with the window, a shaft extending across the upper portion of the window frame, fixed brackets for rotatably supporting the shaft, gears secured to the opposite ends of the shaft in position to engage the racks, and a coiled spring operable to rotate the shaft and gears in the window lifting direction to exert a lifting force upon the window.

2. In combination with a window mounted for vertical sliding movement in its supporting frame, racks secured to the opposite sides of the window to move therewith, a shaft extending across the upper portion of the window frame, fixed brackets at the opposite sides of the window for rotatably supporting the shaft and each formed with a gear enclosing casing, gears rigidly secured to said shaft within the casings to engage the racks, and a coiled spring operable to rotate the shaft in the window lifting direction to exert a lifting force upon the window.

3. In combination with a window mounted for vertical sliding movement in its supporting frame, racks secured to the opposite sides of the window to move therewith, fixed brackets supported at the opposite sides of the window frame near its upper end and each bracket having a gear casing, a gear mounted in each casing to engage said racks, a shaft for rotating said gears, and a coiled spring acting upon the shaft to rotate the gears in the window supporting direction.

4. In combination with a window mounted for vertical sliding movement in its supporting frame, racks secured to the opposite sides of the window to move therewith, fixed brackets supported at the opposite sides of the window and each having a gear casing, a gear mounted in each casing

- to engage said racks, a shaft extending across the window frame from one gear to the other to rotate the gears, and a coiled spring surrounding said shaft and having 5 one end anchored to one of said brackets and the other end secured to said shaft to rotate the gears in the window supporting direction.
5. In combination with a window 10 mounted for vertical sliding movement in its supporting frame, racks secured to the opposite sides of the window to move therewith, fixed brackets supported at the opposite sides of the window frame near its upper end, a gear supported by each bracket in operative engagement with a rack and positioned to remain in engagement with its rack as the window is raised to its wide open position, a shaft connecting the gears, 15 and a spring coiled about the shaft to rotate it and the gears in the window supporting direction.
6. In combination with a window mounted for vertical sliding movement in its supporting frame, racks secured to the opposite sides of the window to move therewith, fixed 20 brackets supported at the opposite sides of
- the window frame near its upper end, a gear supported by each bracket in operative engagement with a rack, a shaft for rotating 30 said gears, a tube enclosing the shaft, a coiled spring surrounding the shaft within said tube and having one end secured to a bracket and its other end secured to the tube so that the tension of the spring may be 35 varied by rotating the tube relatively to said shaft, and means for securing the tube to the shaft to rotate the latter and the gears in the window lifting direction.
7. In combination with a casing having a 40 closed upper end and an opening in the casing near its upper end, a vertically sliding window for closing said opening, racks secured to the opposite sides of the window to move therewith, fixed brackets mounted 45 upon the upper end of the casing to one side of the plane of the window, gears rotatably supported by said brackets in operative engagement with the racks, and a spring acting upon the gears to rotate them 50 in the window lifting direction.

In testimony whereof, I have signed my name to this specification.

JESSE W. GREER.
